FOLDABLE CABINET

Edward Dickerson Backus and Jack Siegel,
Bennettsville, S. C.

Application July 27, 1948, Serial No. 40,964

1 Claim. (Cl. 312—258)

1

This invention relates to kitchen cabinets.

An object of this invention is to provide a kitchen cabinet which is pre-finished at the mill or factory, and which includes hingedly connected together side and front walls, adapted during the shipping of the cabinet to be folded upon each other so as to form a relatively thin package.

The cabinet by reason of its initially collapsed construction will form a very thin or small package, reducing shipping space and storage space, in addition to providing ease of handling before the cabinet is finally set up for use.

Another object of this invention is to provide a cabinet which is packaged in collapsed form with the parts thereof pre-finished so that the parts including the finish will not be damaged during shipment, and each cabinet may be easily and quickly set up with a minimum of tools, and with little chance of the parts becoming injured during shipment, assembling or handling, either before or after the carton has been opened.

A further object of this invention is to provide a cabinet which is formed of a minimum of parts and wherein the exterior surface of the cabinet is not marred by filled holes, the interior parts being secured to the outer panels from the inside of the outer panels by fastening means which do not project through the outer panels.

A further object of this invention is to provide an improved method of constructing and assembling cabinets which will conserve space and assure the safe arrival of the cabinets in collapsed condition and subsequent safe assembling.

With the above and other objects in view, our invention consists in the arrangement, combination and details of construction disclosed in the drawings and specification, and then more particularly pointed out in the appended claim.

In the drawings,

Figure 1 is a detail front elevation of a cabinet constructed according to an embodiment of this invention, showing the cabinet in assembled or set up position,

Figure 2 is a sectional view taken on the line 2—2 of Figure 1,

Figure 3 is a fragmentary sectional view taken on the line 3—3 of Figure 2,

Figure 4 is a fragmentary sectional view taken on the line 4—4 of Figure 2,

Figure 5 is a fragmentary sectional view taken on the line 5—5 of Figure 2,

Figure 6 is a detail front elevation, partly broken away, of the cabinet in collapsed position,

2

Figure 7 is a fragmentary sectional view of the cabinet in collapsed position,

Figure 8 is a detail rear elevation of a modified form of this invention,

Figure 9 is a fragmentary sectional view taken on the line 9—9 of Figure 8,

Figure 10 is a sectional view taken on the line 10—10 of Figure 9,

Figure 11 is a fragmentary top plan of one corner of the cabinet shown in Figures 8 to 10,

Figure 12 is a diagrammatic view in perspective, showing the manner in which the cabinet is initially assembled,

Figure 13 is a perspective view showing the cabinet in partially assembled condition,

Figure 14 is a perspective view showing another step in the assembling of the cabinet,

Figure 15 is a perspective view showing the cabinet in substantially assembled condition,

Figure 16 is a perspective view looking from the bottom showing the mounting of the bottom rail or board,

Figure 17 is a perspective view of the cabinet in completely assembled condition.

Referring to the drawings and first to Figures 1 to 7 inclusive, the numeral 20 designates generally a front wall or panel and the numerals 21 and 22 designate generally opposite side walls which are hingedly connected to the opposite edges of the front wall 20 as will be hereinafter described. The front wall 20 is formed adjacent the opposite vertical edges thereof and on the rear or inner side with vertical grooves 23 within which tongues 24 carried by the side walls 21 and 22 are adapted to engage when the cabinet is in assembled condition.

The side wall 21 has secured adjacent the upper portion thereof a horizontally disposed strip or reinforcing bar 25 which may be secured by glue or other fastening means, and the side wall 21 also has fixed to the inner side thereof a lower horizontally disposed bottom wall supporting bar 26. The side wall 21 is hingedly connected to the adjacent portion of the front wall 20 by means of a pair of L-shaped hinge members 27 which are fixed by fastening means 28 to the upper and lower reinforcing bars 25 and 26 and the hinge members 27 have the forward side or leg 29 thereof pivotally secured on a pivot member 30 which engages in the upper and lower reinforcing bars 31 and 32 fixed to the inner side of the front wall 20.

The side wall 22 is hingedly secured to the opposite portion of the front wall 20 by means 55 of upper and lower L-shaped hinge members 33

which are fixed by fastening means 34 to the upper and lower reinforcing bars 25 and 26, and are pivotally secured on a pivot member 35 engaging the upper and lower rails or bars 31 and 32. The forward leg or side 36 of the hinge member 33 is substantially shorter in length than the forward leg or side 29 so that when the cabinet is in collapsed position, as shown in Figure 6, the side member 22 will be disposed in confronting position to the front wall 20 and the side member 21 will be disposed in overlapping position with respect to the side 22.

The side walls 21 and 22 also have fixed thereto intermediate bars or strips 37, and the front wall 20 has fixed thereto an intermediate rail or bar 38. The rail or bar 38 provides a supporting means for the forward ends of a pair of drawer guide and supporting members 39. The front bar or rail 38 is formed with a reduced thickness portion 40 and the opposite ends 20 of the drawer guide bars 39 are formed with slots 41 so that the forward ends of the guide members 39 will loosely engage the reduced rail portion 40.

An upper drawer guide member 42 is provided with slotted opposite ends 43 which at their forward ends engage reduced thickness portions 44 formed in the upper rail or bar 31. A rear wall or panel 45 is secured to the rear of the cabinet, the side walls 21 and 22 being formed with rabbits 46 within which the rear wall or panel 45 is adapted to engage and fastening means 47 in the form of screws or the like are extended through the rear wall or panel 45 and threaded into the rear ends of the upper and lower reinforcing bars 25 and 26.

The rear wall or panel 45 has secured to the forward or inner side thereof an upper bar 48 having reduced intermediate portions 49 within which the slotted rear ends of the upper guide bars 42 are adapted to loosely or floatingly engage. An intermediate horizontal bar 50 is also fixed to the inner side of the rear wall or panel 45, being formed with reduced thickness portions 51 within which the slotted rear ends of the drawer guide members are adapted to loosely or floatingly engage.

The front wall 20 is formed with a pair of drawer openings 52 through which drawers 53 are adapted to slidably engage, and the drawers 53 are formed with a slot 54 in the rear wall 55 thereof so that the rear or inner portion of the drawer will slidably engage the guide bar 39 which latter member will hold the drawer against undue lateral movement, but in view of the loose mounting of the guide bar 39 the front wall or panel 56 of the drawer 53 will be able to engage flat against the forward side of the front wall 20.

The front panel or wall 20 is also formed with a pair of relatively large openings 57 which are closed by means of doors or closure members 58 mounted on hinges 59. A door pull 60 is secured to each door or closure 58, and a conventional spring bolt 61 is adapted to hold the door 60 in closed position. A vertically disposed reinforcing bar 62 is secured by fastening means 63 to the inner side of the front wall 20 between the door openings 57. When the side walls 21 and 22 are in assembled condition, an angle member 64 is secured at the joint between the side and front walls as shown in Figure 2.

The back or rear wall 45 has fixed to the lower portion thereof a lower reinforcing bar 65 which also constitutes a bottom supporting rail for 75

supporting the rear portion of a bottom panel 66. The bottom panel 66 is adapted to engage on the lower rails or bars 26 carried by the side walls 21 and 22, and engage on the front rail 5 or bar 32 and also on the rear bar or rail 65. A reinforcing bar 67 is secured to the lower side of the bottom member 66, extending between the front and rear bars or rails 32 and 65, and at least one fastening member or screw 68 is extended through the bottom member 66 and the reinforcing bar 67 and is threaded into a rearwardly offset vertical wall 69 which is formed with a tongue at the opposite ends thereof engaging in a vertical groove 70 formed in each of the side walls. It will be understood that any suitable top wall such as 71 or the like may be fixed to the top of the cabinet.

Referring now to Figures 8 to 11, there is disclosed a wall cabinet which is formed of a front wall 72, opposite side walls 73, a rear wall 74 and top and bottom walls 75 and 76. The side walls 73 are hingedly connected to the front wall 72 in the same manner as the side walls 21 and 22 are connected to the front wall 20 so that the side walls 73 may be collapsed to a parallel and overlapping position with respect to each other and parallel with the front wall 72. The side walls 73 are provided with upper and lower grooves 76a and 77 within which top and bottom walls 75 and 76 are adapted to engage and reinforcing bars 78 and 79 are fixed to the upper and lower portions of the side walls 73 and provide a supporting means for the top and bottom walls 75 and 76.

The front wall 72 has a reinforcing bar 80 fixed to the upper portion thereof and a lower reinforcing bar 81. The rear wall 74 has fixed to the forward or inner side thereof upper and lower reinforcing bars 82 and 83 respectively, which have their upper edges flush with the side bars 78 and 79 respectively.

In order to hang the wall cabinet on the wall, a pair of horizontally disposed V-shaped bars 84 and 85 are fixed to the wall 86 and a complementary pair of V-shaped bars 87 and 88 are fixed to the rear side of the rear wall 74 and are adapted to engage the stationary bars 84 and 85 as shown in Figure 9. In this manner the wall cabinet will be firmly supported from the wall, but at the same time may be removed from the wall if desired.

It will be understood that the cabinets hereinbefore described will be completely finished at the mill or factory and when the cabinets are stored or shipped, the cabinets are collapsed after the manner shown in Figure 6. The bottom panel 66 may be disposed on top of the collapsed side wall 21 and the back or rear panel 45 may be disposed over the bottom panel 66.

As shown in Figure 3, one or more shelves 89 may be disposed in these cabinets, being positioned in selected vertically spaced relation with respect to the bottom wall by means of angle-shaped brackets 90 having studs 91 engaging in selected holes 92 formed in the side walls of the cabinet. The collapsed cabinet such as the cabinet shown in Figure 6 may be placed in a carton 93 and when the receiver initially sets up the cabinet, the cover of the carton 93 is removed and the carton with the collapsed cabinet may be set on the floor or other plane surface. The side walls such as 21 and 22 may be swung upwardly as shown in Figure 12, to a substantially vertical position and then the bottom wall 66

may be engaged between the side walls 21 and 22, as shown in Figure 13. With the bottom wall 66 in assembled position, the back wall 45 may then be secured to the side walls 21 and 22, as shown in Figure 14. At this time the cabinet is in substantially assembled condition and the cabinet still partially disposed within the carton 93 is then turned upright, as shown in Figure 14 and the carton removed.

The inner foot rail or board 69 may at this time be engaged in the grooves 70 of the side walls 21 and 22 by tilting the cabinet rearwardly as shown in Figure 16. When the cabinet is in its collapsed position the door pulls or handles 68 are reversed, being secured on the inner sides of the doors, as shown in Figure 6 so that the door pulls or handles 68 will not project from the doors and will not be injured or require additional filling means in the carton before the cabinet is set up.

When the cabinet is set up the handles may be reversed to position them on the forward sides of the doors and the drawers which are separately packed in assembled condition may then be slid into the drawer openings 52. A suitable top wall 25 may be secured to the top of the cabinet and the completely assembled cabinet may then be disposed in a fixed position within a kitchen or other room.

With a construction and method as hereinbefore described, the cabinet is completely finished and suitable wax paper or the like may be interposed between the finished surfaces of the parts so that the parts will not stick together. This manner of constructing a cabinet will conserve a great amount of space both in shipment and storage and will also provide means whereby the cabinet will not be damaged in handling so that the assembled cabinet will be in the same condition as when initially constructed and finished at the mill or factory.

We do not mean to confine ourselves to the exact details of construction herein disclosed but claim all variations falling within the purview of the appended claim.

What we claim is:

A cabinet adapted to be prefinished and

shipped in collapsed form, and forming in assembled set-up condition a rigid cabinet comprising a front wall, side walls, a back panel, a bottom wall, and vertical reinforcing bars secured to said front wall, and of slightly lesser length than the height thereof, adjacent the sides thereof, vertical grooves in said front wall outwardly of said bars, tongues on the edges of said side walls engageable in said grooves and flat L-shaped hinge members each having one leg pivotally secured to one end of one of said reinforcing bars and the other leg fixedly secured to an adjacent edge of one of said side walls; the pivotally secured legs of the hinges secured to opposite ends of one of said reinforcing bars being longer than those secured to the other of said reinforcing bars and the pivotally secured longer leg having its pivot spaced a greater distance from the adjacent side wall and the outer vertical edge of its associated reinforcing member than the pivot point of the other pivotally secured leg is spaced from its adjacent side wall and the outer edge of its associated reinforcing member whereby said side walls will fold in overlapping relation.

EDWARD D. BACKUS.
JACK SIEGEL.
